UNITED STATES PATENT OFFICE.

MARY K. MORSE, OF PHILADELPHIA, PENNSYLVANIA, EXECUTRIX OF HENRY G. MORSE, DECEASED, ASSIGNOR TO NEW YORK SHIPBUILDING COMPANY, OF CAMDEN, NEW JERSEY, A CORPORATION OF NEW JERSEY.

PUNCHING-MACHINE.

No. 796,523

Specification of Letters Patent.

Patented Aug. 8, 1905.

Application filed July 13, 1903. Serial No. 165,275.

To all whom it may concern:

Be it known that HENRY G. MORSE, deceased, late a citizen of the United States of America, and a resident of the city and county of Philadelphia, State of Pennsylvania, did invent certain new and useful Improvements in Punching-Machines, of which the following is a true and exact description, reference being had to the accompanying drawings, which form a part thereof.

The invention relates to punching-machines, and has for its object to provide an improved machine of this kind, and particularly to provide in a convenient and simple manner for the location of the punch in contact with the work and in correct alinement prior to the application of power to perform the punching operation, the machine also providing for the withdrawal of the punch from its work by novel and convenient appliances.

The nature of the improvements will be best understood as described in connection with the drawings, in which it is illustrated, and in which—

Figure 1 is a plan view of the punching-machine; Fig. 2, a side elevation thereof; Fig. 3, a front elevation on a larger scale; Fig. 4, a vertical sectional view, also on a larger scale, taken as on the section-line 4 4 of Fig. 1. Fig. 5 is a longitudinal section through the controlling-valve; Fig. 6, a perspective view illustrating the details of the latch-actuating device; Fig. 7, a perspective view illustrating the details of the latch proper, and Fig. 8 a sectional elevation of the lower end of the punch proper.

A indicates the frame of the machine, having a platform A', upon which rests the punch-die, (indicated at B.) The frame has also an overhanging portion A², to which is attached the head C, carrying and supporting the punch-actuating mechanism.

A³ indicates lugs extending down from the overhanging portion A² of the frame and supporting a pivot-pin for the stripping-lever.

The head C is formed with a vertical channel C', communicating at bottom and top with bearing-sections C² and C³, the upper bearing-section communicating in turn with an enlarged passage, (indicated at C⁴.) In the forward part of the head is formed a cylindrical channel (indicated at C⁶) connecting with a

cylindrical channel C⁶ of smaller diameter, said last-mentioned channel opening through the front of the head, as indicated at C⁷, and communicating with a bearing-section C⁸, above which the head is chambered out, as indicated at C⁹.

D is the cylinder-head of the actuating mechanism, the cylinder formed therein being indicated at D² D³, indicating a stuffing-box in which is situated packing G, held in place by a gland G'.

D⁴ is a port leading into the top of the cylinder, and D' D' &c., are ears extending out from the head D, and perforated for the passage of bolts E E, &c., which secure the head to similar ears C¹⁰ C¹⁰, &c., on the head C.

F is a plunger moving in the cylinder D², having a narrowed lower end, (indicated at F¹.) upon which is secured the annular ring H, supporting the head H', centrally perforated, as indicated at H².

I is the actuating-plunger, having a head I', which is secured between the head of the plunger F and its head H', as shown. The lower end of this plunger is threaded, as shown at I², and has secured upon it the sleeve O, which moves in the cylindrical chamber C⁶ and has secured to its end the sleeve O², which moves in the cylindrical chamber C⁶.

O' is a lateral opening through the sleeve O, O² indicating wrench attachments on the lower end of the sleeve O² by which it can be adjusted.

P is the punch-holding plunger, which moves freely in the sleeve O, P' indicating the upper head of this plunger and P² an annular groove formed therein and having a sloping lower shoulder, (indicated at P³.)

P⁴ is a collar formed near the lower end of the plunger and having secured to it oppositely-extending rods P⁵ P⁶, P⁶ indicating the lower end of the plunger in which the punch is fastened and P⁷ P⁷ indicating springs which support a portion of the weight of the plunger and its attachments, for purposes to be hereinafter explained.

Q is a latch having a beveled lower surface Q' (see Fig. 7) and a slot Q². This latch slides in a laterally-extending box O⁵, secured to register with the opening O' of the sleeve O through flanges indicated at O⁴, having an opening through its top side, as indicated at O⁶,

on each side of which are upwardly-extending lugs, (indicated at O^7 .) As shown, the latch Q has in the box O^5 and directly behind it a sliding piece R , which is forced forward against the latch by a spring Q^8 and with which is engaged the actuating-lever R' , pivoted at R^2 and having an upwardly-extending shoulder pivoted at R^3 . (Best shown in Fig. 7.)

S is a head-bearing secured to the front of the head C and in which is guided the slide S' , which is adjusted and held to proper position by the adjusting-screw, (indicated at S^2 .)

S^3 is a latch projecting through the slide S' , having its rear portion extending through a box S^4 , secured to the slide and containing a spring S^5 , which throws the latch inward.

S^6 is a cam-lever secured on the end of the latch-stem, by which it can be withdrawn at will.

The front end of the latch S^3 is beveled, as indicated at s , Fig. 6.

T is a plate slidably secured between the guides S and S' and having an inwardly-extending arm T' , carrying a roller T^2 , which lies immediately above the projecting lug R^3 of the lever R' . The slide T is formed with a latch-perforation, (indicated at T^3 ,) which is normally engaged by the latch S^3 .

U (see Figs. 4 and 5) is a valve-casing having formed in it a cylindrical chamber U' , into which opens the three ports U^2 U^3 and U^4 .

U^5 is the piston-valve, moving in the valve-chamber U' and actuated by a hand-lever U^6 .

V is the conduit for pressure fluid, opening into the port U^2 .

U' is a conduit leading from the port U^3 to the port D^4 of the cylinder D' .

V^2 is an exhaust-conduit leading from the port U^4 , and V^3 is a conduit leading from the conduit V to the port K^2 of the cylinder K' .

W is a stripping-lever pivoted on the lugs A^3 and having forked ends W^1 W' , which extend over the work on each side of the punch. The lever W has secured to it the stem W^2 , which moves in the guide-bearing C^2 C^3 and has secured to its upper end, which projects through the chamber C^4 , a head W^3 against which a spring in the chamber C^4 presses.

W^5 is an adjusting-nut screwing on the lower portion of the rod W^2 and by means of which the stripping-lever is adjusted to proper height for the different classes of work.

X is the punch secured in the end of the plunger P and preferably formed, as is best indicated in Fig. 8, with a central projecting point X' .

Z indicates the work, a metal plate, and $Z' Z'$ center-punches formed in the plate at the center of the intended holes to be punched therein.

Z^2 Z^3 indicate the punch-holes.

It will be obvious that the conduit V will always be in communication with the cylinder K' through the conduit V^3 , and when not overcome by a greater force the fluid acting on

the sliding cylinder L' will force it up, drawing up the head M , and, through the rods N N , drawing up the head H and piston F . When the valve U^5 is thrust upward to connect the ports U^2 and U^3 , the pressure fluid will flow through the conduit V' into the cylinder D^2 and acting on the plunger-piston F will press it and the plunger I , attached to its lower end, downward, while as soon as the valve U^5 is drawn down to connect the ports U^3 and U^4 the pressure fluid in the cylinder will exhaust and the plunger-piston be raised by the cylinder K , as described.

The normal non-operative position of the mechanism is that shown in Fig. 4, with the punch X resting on the work with simply the weight of the plunger P and its attachments, less the tension in the springs P^7 P^7 , resting upon it. This permits the plate to be moved readily beneath the punch until the point X' of the punch drops into one of the punch-marks Z' , thus finding the center of the hole to be punched. The operator then admits the pressure-fluid to the cylinder D^2 , depressing the plunger I with the sleeves O and O^2 until the top of the plunger I comes in contact with the top of the plunger P at or just before which the downward motion of the cylinder O brings the top of the latch Q below the top edge of the groove C' , whereupon the spring Q^8 forces the latch into the groove C' , all the parts moving down together and the punch being forced through the plate Z , forming a perforation Z^2 . The cylinder D^2 being then connected with the exhaust, the piston F and the plunger I rise, carrying with them the plunger P and the punch by reason of the engagement of the latch Q with a groove C' . The stripping-lever W holds down the work while the punch is being withdrawn from the punched hole Z^2 , and all the parts rise together until the projecting arm R^3 of the lever R' comes in contact with a roller T^2 on the arm T' , the further lifting rocking the lever R' backward, withdrawing the latch Q , and permitting the plunger P to fall down until the punch again rests upon the work Z .

In case any unusual and dangerous pressure is exerted on the arm T' , the breakage of the machine is avoided by the fact that the arm T' is held on the head T , which is free to move up when the pressure exerted upon it is sufficient to push back the latch S^3 , and when it is desired for any reason to retain the plunger P in elevated position it is only necessary for the operator to take hold of the cam-lever S^6 and turn it upward, which will withdraw the latch S^3 from engagement with the head T .

Having now described the said invention, what is claimed as new, and desired to be secured by Letters Patent, is—

1. In a punching-machine, a separate punch-holding device freely movable to and away from the work in combination with a recipro-

cating punch-actuating device arranged to impinge and actuate the holder during its working stroke, a latch arranged to couple the holder and actuating device during the working stroke and a latch-releasing device acting to withdraw said latch and uncouple said parts during the return stroke, and whereby the punch after being withdrawn from the punch-hole is allowed to fall back on the work in advance of the next working stroke.

2. In a punching-machine, a separate punch-holding device freely movable to and away from the work in combination with means for counterbalancing a part of the weight thereof, a reciprocating punch-actuating device arranged to impinge and actuate the holder during its working stroke, a latch arranged to couple the holder and actuating device during the working stroke and a latch-releasing device acting to withdraw said latch and uncouple said parts during the return stroke, and whereby the punch after being withdrawn from the punch-hole is allowed to fall back on the work in advance of the next working stroke.

3. In a punching-machine, a separate punch-holding device freely movable to and away from the work in combination with a punch having a central projecting point, a reciprocating punch-actuating device arranged to impinge and actuate the holder during its working stroke, a latch arranged to couple the holder and actuating device during the working stroke and a latch-releasing device acting to withdraw said latch and uncouple said parts during the return stroke, and whereby the punch after being withdrawn from the punch-hole is allowed to fall back on the work in advance of the next working stroke.

4. In a punching-machine, the combination of a punch-holding plunger P having a latch-recess P^2 with a reciprocating punch-actuating plunger, a sleeve O secured to the actuating-plunger and serving as a bearing for the punch-plunger, a latch secured to the sleeve and arranged to engage the recess P^2 when the actuating-plunger makes its working stroke and a latch-releasing device arranged to with-

draw the latch during the return stroke of the plunger.

5. In a punching-machine having in combination, the actuating-plunger I and punch-holding plunger P and a latch for coupling said plungers together, a latch-releasing device secured to the frame of the machine, and means whereby said releasing device can move under unusual pressure.

6. In a punching-machine having in combination, the actuating-plunger I and punch-holding plunger P and a latch for coupling said plungers together, a latch-releasing device adjustably secured to the frame of the machine and means whereby said releasing device can move under unusual pressure.

7. In a punching-machine having in combination, the actuating-plunger I and punch-holding plunger P and a latch for coupling said plungers together, a latch-releasing device, a latch securing the latch-releasing device to the frame of the machine, said latch being retractable under unusual pressure, and means for withdrawing the latch at will.

8. In a punching-machine, a plurality of plungers, means for connecting the same during their operative stroke, and means for disconnecting the plungers during their return travel.

9. In a punching-machine, a plurality of plungers, means for automatically connecting the same together, and means for automatically disconnecting the plungers during their travel to permit an independent descent of the released plunger.

10. In a punching-machine, a pressure-plunger, a punch-plunger, and means constructed and arranged to automatically connect said plungers together at the downward limit of their movement and to disconnect the same at the upward limit of their movement.
